(No Model.)

J. H. WHITTINGTON.
PERMUTATION PADLOCK.

No. 550,668.

Patented Dec. 3, 1895.

Fig.1

UNITED STATES PATENT OFFICE.

JOSEPH H. WHITTINGTON, OF BUFFALO, NEW YORK.

PERMUTATION-PADLOCK.

SPECIFICATION forming part of Letters Patent No. 550,668, dated December 3, 1895.

Application filed March 23, 1895. Serial No. 542,893. (No model.)

To all whom it may concern:

Be it known that I, JOSEPH H. WHITTINGTON, a citizen of the United States, residing in Buffalo, in the county of Erie and State of New York, have invented certain new and useful Improvements in Combination-Locks, of which the following is a specification.

This invention relates to an improved combination-lock for use on bicycles, desks, drawers, and safes, or for any purpose for which a combination-lock is adapted, and will be fully and clearly hereinafter described and claimed, reference being had to the accompanying drawings, in which—

Fig. 1 is a front elevation of one half of the case of the lock, the other half of the case carrying the combination-index and operating shell and knob being removed, so as to expose the interior locking mechanism, showing one position of the parts when locked. Fig. 2 is a similar view, the tumblers, washers, and throw-off plate being removed, showing the locking plate and bolt in a locked position. Fig. 3 represents a view similar to Fig. 2, showing the same parts in an unlocked position. Fig. 4 is a front elevation of the throw-off plate in position on the locking-plate, showing the bolt and throw-off plate in its unlocked position. Fig. 5 represents a similar view of the throw-off plate in position on the locking-plate, showing the position of these parts when locked. Fig. 6 is a front elevation of the lock complete. Fig. 7 is a detached front elevation of one of the tumblers operating between the throw-off plate and the top tumbler. Fig. 8 represents a detached front elevation of the top or outside tumbler. Fig. 9 represents a transverse section through a complete lock on or about line $a a$, Figs. 3 and 6, looking in the direction of the arrow V, showing the position of the several parts when the lock is put together. Fig. 10 represents a detached front view of one of the washers that intervene between the tumblers. Fig. 11 is a side elevation showing a central section through the locking-plate and its tumbler and washer-holder. Fig. 12 is an inside front elevation of the front half of the case, showing the inside portion of the knob and the operating-shell. Fig. 13 represents a back view of the hasp when the lock is adapted for use as a padlock. Fig. 14 repre-

sents a modification, in which the hasp is omitted and the lock thereby adapted to be used for a drawer or for other analogous purposes.

Referring to the drawings in detail, 1 and 1^a represent the outside case. As will be seen, it is made in two halves, which are preferably constructed of sheet metal stamped up into the desired form in a die of any well-known construction. The top of the case is provided with two openings 2 and 2^a, which are made by cutting corresponding openings in the rims of each half of the case, so that when put together they form the openings 2 and 2^a.

The hasp 3 is pivoted by a pin 3^a in the opening 2^a, and when locked the opposite end passes into the opening 2. When the two valves of the case are put together, they are rigidly secured by screws or rivets 4. The hasp 3 is only used when the device is adapted for use as a padlock for bicycles or other analogous purposes. The lock can be adapted for other uses, such as doors, safes, or desks, by simply changing the shape of the opening in the rim of the locking-plate, as will be more clearly hereinafter shown.

To the half 1 of the case is secured by rivets, or in any well-known way, a locking-plate case 5. (Shown in Fig. 9.) It is provided with an upwardly-extending rim 5^a, having limiting openings 6 for limiting the movement of the locking-plate either way; also, with an opening 6^a, through which one end of the bolt passes. Into this locking-plate case is fitted the locking-plate 7, so that it can turn easily therein. It is provided with an inward-extending peripheral rim 7^a and a radially-extending pin 8, which is located in the opening 6, (see Figs. 1, 2, and 3,) and thereby limits the distance the locking-plate can be turned either way. The locking-plate 7 is also provided with a tubular barrel 9, open at one side 10, and in the plate is an opening 11, extending radially from the opening 10 in the barrel, and directly opposite the opening 11 is an opening 6^a, located in the rim 7^a. The openings 11 and 6^a are openings to allow the bolt to pass, as will be more clearly hereinafter shown. There is also an opening 13 in the plate 7 to allow the end 14 of the hasp 3 to pass when the parts are in their unlocked

position, substantially as shown in Fig. 3, and in front of the opening 13 is another opening 15, which prevents the hasp from being opened when the parts are in their locked position, 5 substantially as shown in Fig. 2. The throw-off plate 16 is provided with a central opening 17, which allows it to be easily put over the barrel 9 of the locking-plate and turn easily thereon. On one side of the central opening 10 17 is an inclined cam-opening 18. The object of the cam-opening 18 is to provide an effectual means for throwing the locking-bolt 19 into the position shown in Figs. 1, 2, and 5, when the combination is broken, which is done 15 by turning it in the direction of the arrow W, Fig. 5, the inclined camway thereby moving the bolt into the position shown in said Fig. 5 against the force of the spring 20. When it is turned in the opposite direction until the 20 part 19^a of the bolt 19 is opposite the inclined opening, the spring 20 will immediately force it back again or to the position shown in Fig. 4. The throw-off plate is provided with three 25 peripheral projections 21, 22, and 23, the office of which will appear farther on.

After the throw-off plate is put on to the barrel 9 a washer 24 is put on, (see Fig. 9,) then a tumbler 25, then a washer 24, and the last tumbler 26, then a washer 24. The number of tumblers, and washers above described 30 may be made more or less than the number above mentioned, if desired.

In Fig. 12 I have shown an inside view of the opposite side 1^a of the case. On the inside 35 of this portion of the lock-case is an operating-shell 34, (see Figs. 9 and 12,) which is rigidly secured to the index-knob 35, so as to move with it. The index-knob 35 is provided with a reduced portion 36, (see Fig. 9,) which 40 passes easily through a circular opening in that side of the case until stopped by the surrounding shoulder or flange 37. The operating-shell 34 is then rigidly attached to the inner end of the knob, substantially as shown in 45 said Fig. 9. In the peripheral edge of this operating-shell are three openings 38, 39, and 40, (see Fig. 12,) where these openings are shown. When the two halves of the shell or case are 50 put together and secured by the rivets 4, the projections 21, 22, and 23 on the throw-off plate pass into the opening 38, 39, and 40, so that when the knob 35 is turned in either direction the throw-off plate will turn with it. The outside of the base or flange 37 of the 55 knob 35 is provided with a series of figures forming the dial arranged in a circle—in this instance, from 5 to 50, (see Fig. 6,)—where this is shown.

The operation of the lock is as follows: For 60 illustration, we will call the combination "5," "15," and "43." Turn the dial-knob 35 in the direction of the arrow X (see Fig. 6) four times or more around and until the numeral "5" is opposite the index-mark 27. This 65 operation brings the last tumbler 26 in position, so that its opening 29 will be opposite

the part 19^a of the bolt 19, thereby leaving the opening free for that portion of the bolt to pass into it. This is done by the pin 30 (shown in Figs. 1, 4, 5, and 9) coming in contact with the shoulder 31 on the tumbler 25, which causes its pin 32, when it comes in contact with the shoulder 33 on the tumbler 26, to move it. Then turn the index-knob 35 around twice in the opposite direction until the dial-number "15" is opposite the index-mark 27, which operation causes the pin 30 to come in contact with the opposite side of the shoulder 31 on the tumbler 25, and move it so that its opening 41 will be in position for the portion 19^a of the bolt 19 to pass into it. Then turn the knob 35 in the opposite direction until "43" is indicated at the index-mark 27. This operation brings the throw-off plate into the position shown in Fig. 4, and the 85 bolt is free to be moved by the spring 20 into the openings, which operation causes the back end 19^e of the bolt 19 to pass out of the opening 6^a in the stationary locking-plate case, thereby releasing the bolt from said case and 90 locking all the tumblers and the locking-plate, so that all move together. Now by turning the knob in the opposite direction the hasp is thrown into the position shown in Fig. 3, thereby opening the lock. 95

I will mention here that the washers 24 are kept from turning on the barrel 9 by the inner projecting shoulders 42 and 42^a, (see Figs. 1 and 10,) which fit in the opening 10 in said barrel 9, substantially as shown in Fig. 1. It 100 is also provided with an opening 43 to allow the part 19^a of bolt 19 to enter.

To brake or throw out the combination and lock the device turn the knob 35 in the direction indicated by the arrow X, Fig. 6, 105 thereby rotating the locking-plate 7 until pin 8 strikes the shoulders 44, which operation brings the end 19^e of the bolt 19 opposite the opening 6^a. The inclined face of the cam-opening 18 of the throw-off plate 16 being in contact with the part 19^a of bolt 19 pushes the bolt so that its end 19^e passes through the opening 6^a in the stationary locking-plate case, thereby freeing all the tumblers, so that a continued turning will throw them all out, 115 thereby preventing the lock from being opened unless the true combination is known.

I claim as my invention—

1. In a combination lock, the combination with the holding case, an operating knob 120 mounted so as to turn on the holding case and carrying an index dial, a throw off plate having an upward projecting portion, a locking plate provided with a barrel upon which the throw off plate is mounted, means connecting the throw off plate with the operating knob, a series of movable tumblers mounted on said barrel and provided with shoulders, and upward projecting stops located beyond the periphery of the tumblers, the tumblers alternating with stationary washers, a locking plate, a locking spring bolt mounted 125 130

on said plate, a fixed holding mechanism and means for connecting or disengaging the bolt therefrom, substantially as described.

2. In a combination lock, the combination 5 with a fixed locking plate case, an opening in the side of said fixed case through which one end of the locking bolt passes, of a locking plate having a barrel carrying an alternate series of washers and tumblers having an 10 opening on their inner sides and upward portions beyond their peripheries, a locking bolt, a throw off plate for forcing one end of the bolt into said opening in the locking plate case and the other portion of the bolt from 15 the opening in the tumblers and washers, substantially as and for the purposes described.

3. In a combination lock, the combination 20 with a fixed mechanism secured to the lock case, of a movable mechanism adapted to turn therein consisting of a locking plate provided with a barrel having an opening extending through it and into the plate, a movable throw off plate and a series of fixed washers mounted on said barrel with an alternating series of tumblers, all having side 25 openings, each tumbler being provided with a stop adapted to operate against the shoulder of another tumbler and move it, and means substantially as above described connected with the throw off plate for operating it.

4. In a combination lock, the combination of a fixed mechanism for locking the bolt 19, a movable locking plate having a barrel carrying an alternating series of washers fixed 35 immovably on said barrel and tumblers movable thereon, and having an opening at one side and provided with shoulders and stops, a locking bolt provided with a spring for holding its head up to and in the side opening in 40 the locking plate, a throw off plate fitted to turn easily on said barrel and provided with an inclined cam opening and means for operating it, whereby the bolt may be forced out of the side openings in the locking plate, 45 washers and tumblers; and thereby release all from the fixed locking mechanism, substantially as described.

5. In a combination lock, the combination of a fixed locking mechanism, with a movable 50 locking plate, means for limiting its movement on the fixed locking mechanism a locking bolt kept to its normal position by a spring, a throw off plate, an alternate series of washers and tumblers having stops and 55 mounted on the locking plate barrel, and means for operating the same, substantially as described.

JOSEPH H. WHITTINGTON.
